UNITED STATES PATENT OFFICE.

FREDERICK F. STRONG, OF BOSTON, MASSACHUSETTS.

ROTARY SPARK-GAP.

SPECIFICATION forming part of Letters Patent No. 775,872, dated November 22, 1904.

Application filed May 23, 1904. Serial No. 209,300. (No model.)

To all whom it may concern:

Be it known that I, FREDERICK F. STRONG, a citizen of the United States, and a resident of Boston, in the Commonwealth of Massachusetts, have invented an Improvement in Rotary Spark-Gaps, of which the following description, in connection with the accompanying drawings, is a specification, like letters on the drawings representing like parts.

10 My invention relates to rotary spark-gaps, the object thereof being to improve the efficiency and durability of the apparatus by preventing the destructive heat effects so common heretofore, removing the interference of the 15 heat with the oscillations, and rendering the oscillations sharp and uniform.

20 A prolific source of trouble in this class of apparatus has been the intense heat produced with the electric oscillations, destroying the electrodes, and rendering the apparatus uncertain and unreliable, and accordingly I have devised the means hereinafter more fully described for obviating these difficulties, consisting 25 of providing a low-resistance arc to operate in connection with said electrodes for drawing away and dissipating the heat or amperage from the latter.

Other novel and advantageous features will 30 also appear in the course of the following description, taken in connection with the accompanying drawings, in which I have illustrated a preferred embodiment of my invention.

In the drawings, Figure 1 is a view in front 35 elevation of my improved spark-gap. Fig. 2 is a top plan view thereof.

40 Mounted on a suitable base a is a wheel or disk a' of conductive material, such as copper or aluminium, journaled in a support a^2 and rotated by any suitable means, as a pulley a^3 . This rotary disk is cut out radially at a^4 to leave a series of discharge-terminals a^5 , coöoperating with a knob-electrode a^6 on the end of a spring a^7 , mounted on a post a^8 and adjustable toward and from the disk electrode a' by a screw a^9 . Besides the radial terminals a^5 the disk a' is provided with an axial terminal a^{10} , coöoperating with an electrode a^{12} , (shown as cup-shaped for the best results,) mounted in a post a^{13} , to

50 which one wire, a^{14} , of the circuit is connected, the other wire, a^{15} , being connected to the post a^8 . It will thus be seen that I provide a double discharge or two gaps in series, a disruptive discharge between the periphery of the disk a' and the knob a^6 , and a low-resistance 55 arc or continuous discharge between the electrodes a^{10} a^{12} .

It will be understood that, excepting as specified in certain of the claims, I do not limit myself to the particular location of the two discharge-gaps nor to the construction of the various parts, as described, although the particular embodiment of my invention which I have above set forth in detail has various advantages presently mentioned.

Having adjusted the terminal a^6 to produce the desired disruptive discharge for which the instrument is intended, I adjust the terminal a^{12} close enough to the knob or other shaped terminal a^{10} to cause a continuous arc, the result being that the surrounding heat is drawn in toward the center of the disk and the surplus heat is dissipated. The vortex of air caused by the rotating disk forms a conductor across the gap a^{10} to a^{12} , which is 75 rendered still better by the heat, and the continuous arc removes the surplus amperage from the other or disruptive-discharge gap, thereby keeping the electrodes a^6 a^6 cool. Moreover, removing the heat from the electrodes a^6 a^6 removes the disturbance thereof with the disruptive discharge which has heretofore caused great uncertainty and irregularity of action, and the oscillations or interruptions are still further sharpened and improved by the square-cut shape of the radial terminals a^5 . By having the discharge radial the distance between the periphery and the adjacent electrode cannot vary in operation, but is uniform, irrespective of any end thrust 90 or longitudinal movement of the shaft, there is a centrifugal draft, due to the radial cuts, which blows out the spark, and the discharge occurs at the region of maximum velocity.

Having described my invention and without limiting myself to all the details described or undertaking to set forth all the variations and uses of which my invention is capable, what

I claim as new, and desire to secure by Letters Patent of the United States, is—

1. A device of the kind described, comprising a fixed disruptive-discharge electrode, a 5 rotary electrode coöperating therewith, and arc-producing means in series therewith located adjacent said electrodes.
2. A rotary electrode and two stationary electrodes in series therewith, and adjusted re- 10 spectively for producing therewith a disruptive discharge, and a continuous-arc discharge.
3. A high-frequency interrupter, comprising means for producing a rapid disruptive discharge, and continuous - arc producing 15 means in series therewith.
4. A device of the kind described, comprising a rotary electrode, a coöperating peripheral disruptive-discharge electrode, and an axial continuous-arc electrode.
- 20 5. A device of the kind described, comprising separated electrodes, and a disk in series

therewith having peripheral terminals to co-operate with one electrode, and an axial terminal to coöperate with the other electrode.

6. A device of the kind described, comprising a disk having a series of peripheral terminals and an axial terminal, a discharge-electrode for the former, and a cup-shaped electrode adjusted close to the axial terminal. 25

7. In a device of the kind described, a rotary-disk electrode, and a coöperating electrode, said disk having a series of radially-extending rectangular terminals for giving sharp oscillations. 30

In testimony whereof I have signed my name 35 to this specification in the presence of two subscribing witnesses.

FREDERICK F. STRONG.
